UNITED STATES PATENT OFFICE.

MICHAEL MARY BROPHY, OF LONDON, ENGLAND.

RADIATOR FOR WARMING BUILDINGS.

SPECIFICATION forming part of Letters Patent No. 665,308, dated January 1, 1901.

Application filed May 26, 1900. Serial No. 18,100. (No model.)

To all whom it may concern:

Be it known that I, MICHAEL MARY BROPHY, a subject of the Queen of Great Britain, residing at 251 High Holborn, London, England, have invented new and useful Improvements in Radiators for Warming Buildings, of which the following is a specification.

My invention relates to heat-radiators for warming buildings and to that class of such radiators provided with hinged leaves or sections for permitting of the thorough cleansing of the same at all parts, the object of my present invention being to simplify the construction of such radiators and reduce their cost.

In the accompanying drawings, Figure 1 is a side elevation of a radiator constructed according to my present invention. Fig. 2 is a plan view of the same. Fig. 3 is a horizontal section through one of the leaf-sections. Fig. 4 is a vertical section of the footpiece upon which the hinged leaf of the radiator turns, and Fig. 5 is a horizontal section taken through the lower part of the radiator-leaf above the footpiece. Fig. 6 is a vertical section of a bearing-wheel for supporting the free end of the leaf.

a is the leaf of a radiator, which, as shown in Fig. 1, is composed of two parts or sections *b b*, each of which is in the form of a hollow plate having hollow vertical tubular portions *c c'* at the ends, as shown clearly in Fig. 3. It is to be understood, however, that a leaf may be composed of a single plate *b* or of more than two of such plates. These plates *b b*, which are placed one upon another, so that their vertical tubular portions are in alinement, are preferably connected together by nipples, such as *d*, (indicated in dotted lines in Fig. 1,) having right and left hand screw-threads, in a well-known manner, the said nipples having internal lugs or ribs to permit of the engagement of a "tommy" or wrench therewith.

The leaf *a* is supported at its pivotal end upon a hollow foot *e*, Figs. 1 and 4, to which the flow and return pipes *f g* of the circulating system are attached, the aperture in the foot to which the flow-pipe *f* is connected having in connection with it inside the foot an elbow *i*, into the open end of which an extension-pipe *j* can be inserted to pass up through the vertical tubular portion *c* to nearly the top of the leaf, whereby the hot water which

enters through the pipe *f* passes to the top of the leaf and after flowing through the sections gravitates down through the space *k* in the foot to the return-pipe *g*.

The connection between the footpiece *e* and the lower end of the adjacent socket *c* is effected through the medium of a connector-ring *l*, screwed or otherwise fixed to the adjacent end of the said vertical tubular portion *c* and provided with a flange *l'*, designed to rotate upon a bearing-surface *l''* in the foot, the said ring being held in position in the foot by means of a kind of gland *m*, adapted internally to fit the exterior of the connector-ring *l* and externally to screw into the upper end of the foot *e*. The flange *l'* of the connector-ring is formed with a groove on the under side to receive a packing-ring *n*, and the bearing-surface *l''*, upon which the said packing-ring rests, is in the form of a rib, which projects into the said groove to form a tight joint to prevent leakage. Between the gland and the upper side of the said flange *l'* I preferably insert a corrugated washer *o*, of spring-steel, which tends to keep the packing-ring *n* in close contact with the bearing-surface *l''*, notwithstanding any wear which may take place between the said ring and this surface.

At the lower end of the lowermost tubular portion *c'* is a bearing wheel or roller *p*, Figs. 1 and 6, capable of rising and falling relatively with the leaf in order to pass over inequalities in the floor.

In order that the same amount of support shall practically be afforded to the leaf *a* at all times, notwithstanding the up-and-down movement of the bearing-wheel *p*, and no additional strain put upon the hinged point of the said leaf when the said wheel is passing over, say, a projection on the floor, as would be the case if the wheel were simply acted upon by a spiral spring, I provide the following arrangement: The bearing-wheel *p* is mounted in bearings in a box *p'*, capable of sliding in an outer box *p''*, which is fixed in the lower end of a tubular portion *c'*, a screw or other pin *p''* being inserted through the outer box *p''* and projecting into a slot *p'''* in the inner box *p'* in order to hold the said inner box within the outer box and at the same time permit of its vertical movement therein. Within the inner box *p'* is placed a spiral spring *q*, the lower end of which rests upon

an annular shoulder q' and the upper end of which carries a bearing-plate q^2 , upon which are pivoted two levers $r\ r$, each of which levers is connected at one end by a link r' to a bridge-piece r^2 , mounted upon the spindle of the roller p and passing over the latter, while their other ends are in contact with a rib or flange s on the inside of the box p^2 .

It will be understood that the spring q is normally under a certain amount of compression suitable to the weight to be supported, the weight being actually carried by the levers $r\ r$ and transmitted through them and the bearing-plate q^2 to the spring q . The position of the point where each link r' and lever r are connected and of the fulcrum of such lever relatively with one another is such that when the leaf a is moved and, say, the wheel or roller p enters a depression in the floor, so that the spring q expands, each lever r will be moved into a more nearly horizontal position, thereby increasing the distance of the line of draft of its link r from the point of pivoting of said lever r , and thus increasing the leverage of the spring upon said lever. The weakening of the expanded spring will therefore be compensated for by the increase in leverage, and the upward stress exerted by the outer ends of levers r upon the shoulder s will remain constant. On the other hand, if the roller or wheel p rises over a projection upon the floor each of the levers $r\ r$ will assume positions more nearly vertical, and the distance between the line of draft of its link r and the point of pivoting will be decreased, and thus decreasing the leverage of the spring. The decreasing of the leverage of the spring will compensate for the increased tension of the compressed spring, and the upward pressure of the outer ends of the levers r upon the shoulder will therefore remain constant. It will thus be seen that the upward pressure of levers $r\ r$ upon the shoulder s remains constant under all conditions.

Having now particularly described and ascertained the nature of my said invention and in what manner the same is to be performed, I declare that what I claim is—

1. In a heat-radiator, the combination with a hollow stationary foot provided with an inlet and discharge aperture, of a radiator leaf or section pivotally connected to said foot and having a hollow vertical portion extending upward from and communicating with said foot and a pipe extending from the inlet of said foot to a point adjacent to the top of said vertical portion of the radiator, substantially as described.

2. In a heat-radiator, the combination with a hollow stationary foot provided with an inlet and discharge aperture and having an aperture in its upper face, a socket to pivotally receive a portion of a radiator-section, of a radiator leaf or section pivotally engaging said socket and provided with a hollow vertical portion in line with said socket and communicating with said foot, a pipe extending

from the inlet of said foot to a point adjacent to the top of the said vertical portion of the radiator and a bearing wheel or roller for supporting the outer end of the radiator, substantially as described.

3. In a heat-radiator, the combination with a hollow stationary foot provided with an inlet and discharge aperture and having an aperture in its upper face, a socket to pivotally receive a portion of a radiator-section, of a radiator leaf or section adapted to be pivotally connected to said foot, a connector-ring secured to said radiator and engaging said socket in the foot, a gland for securing said ring movably in said socket, substantially as described.

4. In a heat-radiator, the combination with a hollow stationary foot provided with an inlet and discharge aperture and having an aperture in its upper face, a socket to pivotally receive a portion of a radiator-section, of a radiator leaf or section adapted to be pivotally connected to said foot, a connector-ring secured to said radiator and engaging said socket in the foot, a gland for securing said ring movably in said socket, said radiator-section having a hollow vertical portion in line with said ring and the socket in said foot and a pipe extending from the inlet in said foot to a point adjacent to the top of the said vertical portion of the radiator, substantially as described.

5. In a heat-radiator having a hinged leaf or section, the combination with a foot upon which the pivotal end of the said leaf is carried, of a bearing-wheel at the free end of the leaf, the weight being supported upon the said bearing-wheel through the intermediary of a spring and pivoted levers whereby the spring acts uniformly under variations in the vertical position of the wheel, substantially as described.

6. In a radiator, the combination with a stationary support provided with inlet and discharge apertures, of a radiator-section having one end pivotally connected to and communicating with said stationary support, and a support for the other end of the radiator-section comprising among its members, an outer box secured to the radiator and having a guiding-aperture in its lower end, a roller and a bearing-box therefor adapted to slide vertically in said guiding-aperture, a movable collar in said aperture a spring interposed between said collar and said bearing-box, a lever mounted on said collar and having a portion in engagement with said outer box and a connection between said lever and said bearing-box whereby said roller will be permitted to move vertically in said outer box without materially affecting the action of said spring, substantially as described.
